UNITED STATES PATENT OFFICE.

THEODORE B. DRESCHER, OF ROCHESTER, NEW YORK.

DESIGN FOR A RADIATOR CAP.

Application filed January 20, 1923. Serial No. 4,947. Term of patent 3½ years.

To all whom it may concern:

Be it known that I, THEODORE B. DRESCHER, a citizen of the United States, residing at Rochester, in the county of Monroe and State of New York, have invented a new, original, and ornamental Design for a Radiator Cap, of which the following is a specification, reference being had to the ac-

companying drawing, forming part thereof. Figure 1 is a front elevation of a radiator cap, showing my new design, and

Figure 2 is a side elevation of the same.

I claim:

The ornamental design for a radiator cap, as shown.

THEODORE B. DRESCHER.
